Primary Examiner — Kevin Rudzinski(74) *Attorney, Agent, or Firm* — Alan Kamrath; Kamrath IP Lawfirm, PA(57) **CLAIM**

The ornamental design for igniter, as shown and described.

DESCRIPTION

FIG. 1 is a perspective view of a igniter showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

Broken lines shown in the drawings illustrate portions of the igniter that form no part of the claimed design.
